UNITED STATES PATENT OFFICE.

WILL EVANS, OF INGLEWOOD, CALIFORNIA.

MOP.

Application filed July 8, 1925. Serial No. 42,206.

My invention relates to mops, more particularly to mops with wringing attachments, and the objects of my invention are: first, to provide a mop which provides a large, flat surface for supporting the mop-cloth; second, to provide a mop of this class with a wringer attachment in connection therewith in which the mop cloth may be wrung relatively dry from end to end; third, to provide a mop of this class in which the mop-cloth may be shifted at the wide end so that in wringing it is practically uniform throughout its length; fourth, to provide a mop of this class in which the handle may be quickly removed or re-positioned relatively to the mop; fifth, to provide a mop of this class in which the handle and wringer attachment may be shifted relatively so that the mop may be operated easily under objects that are close to the floor when desired; sixth, to provide a novelly constructed mop of this class; and seventh, to provide a mop of this class which is very simple and economical to construct, easy to place the mop-cloth on, easy to operate, efficient in its action, durable and which will not readily deteriorate or get out of order.

With these and other objects in view as will appear hereinafter, my invention consists of certain novel features of construction, combination and arrangement of parts and portions as will be hereinafter described in detail, and particularly set forth in the appended claims, reference being had to the accompanying drawings and to the characters of reference thereon, which form a part of this application, in which:

Figure 1, is a top or plan view of my mop structure showing the position of the mop cloth by dotted lines, and showing the handle fragmentarily, and showing a varying position of the mop cloth shifting lever by dotted lines; Figure 2, is a side elevational view of the same and showing the mop positioned thereon by dotted lines; Figure 3, is a sectional view through 3—3 of Figure 2. Figure 4 is a section on the line 4—4 of Figure 2 and Fig. 5 is a view similar to Figure 3, but showing parts in another adjusted position.

Similar characters of reference refer to similar parts and portions throughout the several views of the drawings.

The main mop support 1, cross bars 2 and 3, mop-cloth shifting lever 4, mop handle extension member 5, extension member sup-

port 6, wringer crank supporting clamp 7, wringer crank support 8, wing bolt 9, wringer crank 10, handle 11, and mop-cloth 12, constitute the principal parts and portions of my mop.

The main mop support 1, is preferably made of one piece of wire about one-fourth inch. It is provided on one end with a loop 1^a, which is adapted to receive the opposite end 1^b, which is provided with a right angled curved end, which fits into said loop 1^a. It is bent at an acute angle at 1^c, then extends backwardly, then provided with a short right angle turn 1^d, then extends back approximately parallel and is provided with a loop 1^e, which is adapted to receive the end 5^a of the handle extension 5, then forwardly and provided with a semi-circular curve 1^f, then back approximately parallel and provided with another loop 1^g, then back and with another turn 1^h, then back parallel with an acute angle 1ⁱ, then outwardly and with a curve 1^j, then across providing a front supporting portion 1^k, and with a loop 1^l, terminating in 1^b. This wire member is supported transversely by means of the bar 2 which extends up over the upper surface of the loop 1^f and is looped around the outer side wires near the angles 1^e and 1ⁱ. Bar 2 is provided with a rivet 2^a in its upper surface near one end upon which is pivotally mounted the lever 4. This lever 4 is provided with an upwardly extended handle portion 4^a on one end and at its opposite end with an upwardly turned furcated portion 4^b, which is adapted to engage the mop-cloth and when shifted to the position shown by dotted lines of Figure 1, of drawings, will shift the side of the mop-cloth at 95 the front 1^k to a contracted position ready for wringing. The bar 3 extends over the inner portion of the member 1 and loops around the outer portions the same as bar 2, thus forming rigid supports for main mop-cloth support 1. The handle extension 5 is a U-shaped member which passes through a hole in the handle some distance from the end and extends downwardly along the handle past the ends and is provided with turned portions at the ends which fit into the loops 1^e and 1^g of the member 1, and may be sprung together for removing them from said member 1. In order to support these extended portions there is provided a plate 6, secured to the end of the handle by means of a screw 6^a through which the extended

100
105
110

portions of the member 5 extend. It will be noted that this member 5 is curved as shown best in Figure 2 of the drawings. Mounted on the handle 11 adjacent to the member 5 is a clamp member 7, which is provided with an extended portion 7^a, which is provided with a hole therein in which is mounted the wing bolt 9, which fits into a nut 9^a and is adapted to clamp member 7 onto the handle member 11. This extended portion 7^a is provided with outwardly extended flanges 7^b for reinforcing the same against lateral bending, and mounted in this member 7 is the wringer crank support 8, which is provided with a journal 8^a on its lower end in which the crank member 10 is revolvably mounted and it is provided with a slot 8^b to permit the member 8 to be shifted relatively to the member 7 so that the crank member may be shifted toward the handle to provide for mopping under objects close to the floor. The wing bolt 9 serves to clamp the members 7 and 8 relatively to each other at the same time that the clamp member 7 is clamped onto the handle 11. This member 8 is provided with flanges forming a channel shaped member for reinforcing the same. The wringer crank 8 is provided with a crank on one end and on the opposite end is provided a loop 10^a, which is extended considerably and forms the support for the back portion of the mop-cloth when mopping and serves for twisting the mop when wringing the same. This loop is provided with a large open space 10^b to permit readily placing the mop in position in the loop.

It will be noted that the mop-cloth in this class of structure is an endless cloth in belt form. The one side is positioned over the front member 1^a by depressing the portion 1¹, removing the member 1^b from the loop 1^a, then the mop is positioned over the front member 1^a and the sides extend over the loop 1^a of the loop 1^b on the opposite side, the cloth also being engaged by the furcated portion of the lever 4 as hereinbefore described. The other end of the mop is positioned through the opening 10^b into the loop of the wringer crank. Both portions of the mop-cloth being positioned below the main support and looped over the front portion 1^a and the portion 10^b of the wringer crank 10. When it is desired to wring the mop-cloth, the lever 4 is shifted to the position shown by dotted lines in Figure 1 of the

drawings, thus contracting the end of the cloth positioned over the portion 1^a so that it is approximately the same width as the portion over the portion 10^b of the wringer crank. Then the wringer crank is turned, which twists the mop and wrings the same, after which the crank is released, the mop-cloth spread by shifting the lever 4 back into the position shown by solid lines in Figure 1 of the drawings.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent, is:

1. In a mop of the class described, a flat mop cloth supporting member provided with a relatively wide front portion adapted so to receive the front loop portion of a mop-cloth, a handle pivotally connected to said mop cloth supporting member, a wringer crank member revolvably mounted on said handle provided with a loop adapted to receive the opposite loop end of the mop cloth, a lever member pivotally mounted on said mop cloth supporting member and extending forwardly and adapted to engage the one side of the loop portion of said mop-cloth for shifting the same on the front end of said mop cloth supporting member for contracting the front end of said mop-cloth.

2. In a mop of the class described, a base support provided with a relatively broad front portion for supporting the one end of a mop cloth and a relatively narrow back portion, a handle attached to said support, a wringer loop revolvably mounted on the handle for supporting the opposite end of said mop cloth, a lever member pivotally mounted on the base support provided with an engaging portion adapted to engage and shift the cloth and contract the same on the broad portion of said support.

In testimony whereof, I have hereunto set my hand at Los Angeles, California, this 30th day of June, 1925.

WILL EVANS.
